UNITED STATES PATENT OFFICE

126,676

DESIGN FOR A BATHTUB

Charles H. Widman, Detroit, Mich., assignor to
The Murray Corporation of America, Detroit,
Mich., a corporation of Delaware

Application October 5, 1939, Serial No. 87,532

Term of patent 14 years

To all whom it may concern:

Be it known that I, Charles H. Widman, a citizen of the United States of America, residing in Detroit, in the county of Wayne, State of Michigan, have invented a new, original, and ornamental Design for Bathtub, of which the following is a specification, reference being had to the accompanying drawing, forming a part thereof, wherein:

Fig. 2 is a plan view of the bathtub illustrated in Fig. 1; and,

Fig. 3 is a diagrammatic sectional view of the bathtub illustrated in Fig. 2, taken on the line 3—3 thereof.

The essential features of my design reside in the portions shown in solid lines.

I claim:

The ornamental design for a bathtub, substantially as shown and described.

CHARLES H. WIDMAN.
